UNITED STATES PATENT OFFICE.

FRANK H. TRIMBLE, OF LANKERSHIM, CALIFORNIA.

DESIGN FOR LIGHTING-FIXTURE PLATE.

Application filed August 30, 1926. Serial No. 18,899. Term of patent 3½ years.

To all whom it may concern:

Be it known that I, FRANK H. TRIMBLE, a citizen of the United States, residing at Lankershim, in the county of Los Angeles and State of California, have invented a new, original, and ornamental Design for Lighting Fixture Plate, of which the following is a specification, reference being had to the accompanying drawing, forming part thereof.

Fig. 1 is an inverted plan view of a light-

ing fixture plate, showing my new design, only a portion of the surface ornamentation being completed. It is understood, however, that the unornamented portion within the outline shown involves a mere repetition of the completed portion; and

Fig. 2 is a side elevation of the plate.

I claim:

The ornamental design for lighting fixture plate as shown and described.

FRANK H. TRIMBLE.
